UNITED STATES PATENT OFFICE.

DOUGLAS M. CAMPBELL, OF HOUSTON, TEXAS, ASSIGNOR OF ONE-HALF TO
SINCLAIR TALIAFERRO, OF SAME PLACE.

BALE-BAND FASTENER.

SPECIFICATION forming part of Letters Patent No. 639,695, dated December 19, 1899.

Application filed August 5, 1899. Serial No. 726,302. (No model.)

To all whom it may concern:

Be it known that I, DOUGLAS M. CAMPBELL, a citizen of the United States, residing at Houston, in the county of Harris and State of Texas, have invented a new and useful Bale-Band Fastener, of which the following is a specification.

This invention relates to bale-band fastenings; and it has for its object to provide a new and useful device of this character having simple and efficient means for exerting a powerful tension upon the bale-band, so as to take up all slack therein and secure the same tightly about the bale.

To this end the invention contemplates a bale-band fastening or "buckle" adapted to be applied with the aid of a hand tool or wrench in a manner somewhat similar to the application of the bale-tie covered by my former patent, No. 609,872, issued August 30, 1898; but in the present invention the device includes members which provide for taking up a maximum amount of slack with a minimum movement and also to secure the band against the possibility of loosening or the ends thereof rending apart.

A further object of the invention is to construct the members of the device in such a way that the ends of the bale-band may be quickly fitted thereto, while at the same time providing a construction occupying a comparatively small space and capable of easy manipulation.

Another object of the invention is to provide simple and improved means for positively obviating slipping or breakage of the band and buckle.

With these and other objects in view, which will more readily appear as the nature of the invention is better understood, the same consists in the novel construction, combination, and arrangement of parts hereinafter more fully described, illustrated, and claimed.

The invention essentially comprises in its organization a buckle-plate, through which the ends of the band are threaded, and a locking member or device having a coupling connection with said plate to prevent unbending or unwinding of the lapped ends of the bands after said plate has been turned bodily upon one edge as a fulcrum; but these members

may be combined in various ways and, in fact, divers modifications may be resorted to without departing from the principle of the invention; but the preferred embodiment of the improvements is shown in the accompanying drawings, in which—

Figure 1 is a perspective view of a bale-band fastening constructed in accordance with the present invention, showing the same open in its initial position with the lapped ends of the bale-band threaded therethrough. Fig. 2 is a similar view of the construction shown in Fig. 1, illustrating the buckle-plate as it is being bodily turned through the medium of the hand tool or wrench, the latter being shown in dotted lines. Fig. 3 is a similar view of the fastening or buckle, showing the lapped ends of the band wound upon the buckle-plate and the latter locked against turning. Fig. 4 is a detail in perspective of a modification, showing the parts in position about to be interlocked. Fig. 5 is a detail in perspective of the hand tool or wrench for turning the buckle-plate.

Like numerals of reference designate corresponding parts in the several figures of the drawings.

The bale-band fastening or buckle forming the subject-matter of the present application essentially comprises a buckle-plate 1 and a locking member or catch 2, which in the preferred forms of the invention are preferably pivotally coupled together by a loose coupling 3, as shown in Figs. 1 to 4, inclusive.

In carrying out the invention the buckle-plate 1 constitutes a winding member. This member preferably consists of an approximately rectangular flat plate closed upon all sides and provided therein with a band-receiving eye or opening 4, which is sufficiently large to freely and loosely receive therein the lapped ends of an ordinary bale-band 5, as will be hereinafter more fully explained; and at this point it may be understood that while the device is essentially designed for use as a fastening for the bands of cotton-bales the same is necessarily capable of general application to bands of bales of hay or other packages.

The flat open-center winding member or buckle-plate 1 is provided at the opposite sides

- thereof with what may be properly termed "fulcrum-bars" 6, which constitute integral parts of the plate and are preferably provided with beveled edges 7, that impinge upon the 5 lapped ends of the bale-band and form fulcrum-points, upon which the band bends. On account of these beveled fulcrum edges the bends in the band will be close and sharp, thus insuring a firm engagement of the buckle- 10 plate or winding member with the band, so that slipping of the parts is reduced to a minimum while the plate is being turned to wind up or fold the band thereon.
- In addition to the fulcrum-bars 6 the buckle- 15 plate 1 in the form shown in Figs. 1, 2, and 3 of the drawings has projected from one edge thereof a pair of lateral catch-hooks 8, which coöperate with the lock member or catch 2 in the manner hereinafter explained, the points 20 or bills of said hooks being offset laterally from one of the flat sides of the plate, so as to properly engage with the lock member or catch when the buckle-plate is turned flat upon the bale.
- 25 In the form of the invention shown in Figs. 1 to 3, inclusive, the buckle-plate 1 is also preferably of a tapering width, widening out toward the side opposite the catch-hooks 8, and is provided with a widened side bar 9, 30 which forms a reinforced or strengthened engaging portion for the hand wrench or tool. As already explained, the buckle-plate or winding member 1 is preferably connected with the lock member or catch 2 by the coupling 3, and in the construction shown in said 35 Figs. 1 to 3, inclusive, the lock member or catch 2 is in the form of a rectangular loop or bail and the coupling 3 consists of a wire link. This link comprises a wire body looped 40 at one end to form a pair of pivot-eyes 10, loosely receiving one of the fulcrum-bars 6 of the buckle-plate, said loop being also provided with the parallel side arms 11. The side arms 11 of the wire coupling-link are provided at 45 their ends opposite the pivot-eyes 10 with the elongated or slotted loops 12, which loosely receive one of the side bars of the locking member or bail 2, so that the latter is free to swing in engagement with the catch-hooks 8 50 of the buckle-plate or winding member 1. The said coupling 3, which loosely connects the buckle-plate or winding member 1 with the lock member or catch 2, renders the device perfectly reliable in action and easily 55 manipulated, as the said coupling 3 permits of the necessary free movement of the parts, so that they will readily adjust themselves to the work, while at the same time always maintaining the lock member or catch in operative 60 relation to the hooks of the buckle-plate or winding member.

To provide for applying the device to a bale-band, there is employed a hand wrench or tool 13 of the type disclosed in my former patent, hereinbefore referred to. This hand wrench or tool 13 is provided with the usual ratchet-head 14, in which is fitted the shank 15 of a

turning key or bit 16. The turning key or bit 16 is provided with a wide bifurcated head 17, adapted to engage over and secure a firm purchase upon the widened engaging bar 9 of the buckle-plate, so that the latter may be turned bodily under force to provide for winding up or folding the lapped ends of the bale-band thereon. 75

In applying the device to a bale-band one end of the band 5 is threaded through the locking member or bail 2 and thence under one of the fulcrum-bars 6 of the buckle-plate 1 and through the eye 4 thereof, while the other end of the bale-band is lapped over the aforesaid end and under the said fulcrum-bar. The terminal of the said other end of the band terminates short of the locking member or bail 2, as plainly shown in Fig. 1 of the 80 drawings, so that both terminals of the bale-band will be entirely covered when the fastening device is locked in its closed position, as plainly shown in Fig. 3 of the drawings, thus leaving no protruding ends, as is common in 85 other types of bale-fastenings. After threading the ends of the bale-band through the device, as described, the turning key or bit 16 is engaged with the wide side bar 9 of the buckle-plate and through the medium of the wrench 90 or tool the said plate is turned bodily upon one edge as a fulcrum. Thus being turned, the lapped ends of the bale-band are bent upon the fulcrum-bars 6 and the slack of the band thereby wound upon the buckle-plate. 100 It will be observed that the buckle-plate is only intended to make a half-turn, but in making this turn will wind up thereon double its length or width of the band, thereby taking up a maximum amount of slack with a minimum movement. When the buckle-plate has been completely turned, the operator with his 105 free hand swings the locking member or bail 2 in engagement with the hooks 8, thereby locking the buckle-plate or winding member 110 against backward movement, with a consequent unwinding of the band. If the cotton or other material of the bale is firm, the buckle 115 or fastening will remain in a flat position; otherwise the edge upon which the buckle-plate turns as a fulcrum will bury itself in the cotton or other material and permit the entire fastening to turn slightly endwise; but the tapering width of the plate 1 prevents the locking member or bail 2 slipping materially 120 away from the catch-hook 8.

To unlock the fastener, the wrench or tool may be applied to ease up the buckle-plate to permit of the disengagement of the locking member or bail from the catch-hooks thereof. 125

In the modification shown in Fig. 4 of the drawings precisely the same combination of parts is involved as in the construction illustrated in Figs. 1 to 3, inclusive; but the shape of these parts is slightly changed.

Referring more particularly to the construction shown in Fig. 4 of the drawings, it may be observed that the flat buckle-plate 1 instead of having catch-hooks projecting from

one edge thereof is provided at one side with laterally-offset curved catch-hooks 8^a, which necessarily maintain the same positions as the points or bills of the catch-hooks 8 in the 5 construction already described. In the modification referred to the locking member or bail 2 and the coupling 3 are in the form of substantially U-shaped bails pivotally joined together and the coupling being pivotally connected with one side of the buckle-plate or winding member in order that the operation already described may be carried out. This 10 operation is precisely the same as described in connection with the construction illustrated 15 in Figs. 1 to 3, inclusive.

Other modifications will readily suggest themselves to those skilled in the art, and it will be understood that various changes in the size, shape, proportion, and minor details 20 of construction may be resorted to without departing from the spirit or sacrificing any of the advantages of the invention.

Having thus described the invention, what is claimed is—

25 1. A bale - band fastening comprising a buckle-plate having a band-receiving eye or opening, and adapted to have the slack of the band wound thereon, a locking member, and a coupling between the buckle-plate and the locking member, the said buckle-plate, the locking member, and the coupling connection having the band threaded therethrough.

30 2. A bale - band fastening, comprising a buckle-plate having a band-receiving eye or

opening and adapted to turn bodily upon one 35 edge as a fulcrum, and a locking device for the plate having a swinging coupling connection therewith.

3. A bale - band fastening, comprising a buckle-plate having a band-receiving eye or 40 opening, and a locking member pivotally coupled with the plate and having an interlocking engagement therewith, said locking member, the plate and the coupling connection having the band threaded therethrough. 45

4. A bale-band fastening, comprising a flat buckle-plate having a band-receiving eye or opening, and catch-hooks, a swinging locking-bail, and a coupling-link pivotally connected to said bail and to the buckle-plate. 50

5. A bale-band fastening, comprising a flat buckle-plate adapted to turn bodily upon one edge as a fulcrum, said plate being of a tapering width and provided with a band-receiving eye or opening, and at one side with 55 a pair of lateral catch-hooks, a locking-bail adapted to engage with the catch-hooks of the buckle-plate, and a coupling-link pivotally connected at opposite ends respectively, with one side bar of the buckle-plate, and with said 60 locking-bail, substantially as set forth.

In testimony that I claim the foregoing as my own I have hereto affixed my signature in the presence of two witnesses.

DOUGLAS M. CAMPBELL.
